(57) CLAIM

The ornamental design for a pet bowl as shown.

DESCRIPTION

FIG. 1 is a front, right, and top perspective view of a pet bowl, showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and top perspective view of a second embodiment of the pet bowl;

FIG. 10 is a rear, left, and bottom perspective view of FIG. 9;

FIG. 11 is a front elevation view of FIG. 9;

FIG. 12 is a rear elevation view of FIG. 9;

FIG. 13 is a left side elevation view of FIG. 9;

FIG. 14 is a right side elevation view of FIG. 9;

FIG. 15 is a top plan view of FIG. 9;

FIG. 16 is a bottom plan view of FIG. 9;

FIG. 17 is a front, right, and top perspective view of a third embodiment of the pet bowl;

FIG. 18 is a rear, left, and bottom perspective view of FIG. 17;

FIG. 19 is a front elevation view of FIG. 17;

FIG. 20 is a rear elevation view of FIG. 17;

FIG. 21 is a left side elevation view of FIG. 17;

FIG. 22 is a right side elevation view of FIG. 17;

FIG. 23 is a top plan view of FIG. 17; and,

FIG. 24 is a bottom plan view of FIG. 17.
